UNITED STATES PATENT OFFICE.

ALBERT W. PEARSALL, OF LOWELL, MASSACHUSETTS, ASSIGNOR TO THE LAMSON COMPANY (FORMERLY LAMSON CONSOLIDATED STORE SERVICE COMPANY,) OF BOSTON, MASSACHUSETTS, A CORPORATION OF NEW JERSEY.

PNEUMATIC-DESPATCH-TUBE APPARATUS.

1,311,617.

Specification of Letters Patent. Patented July 29, 1919.

Application filed August 30, 1912. Serial No. 717,833.

To all whom it may concern:

Be it known that I, ALBERT W. PEARSALL, of Lowell, in the county of Middlesex and Commonwealth of Massachusetts, have invented certain new and useful Improvements in Pneumatic-Despatch-Tube Apparatus, of which the following is a specification.

This invention relates broadly to automatic pumping apparatus and more particularly to pneumatic despatch tube systems and the pumping apparatus therefor and has for one of its objects the provision of means for automatically starting an exhauster, blower, pump or the like, which may be broadly termed a pump and which forms a part of the apparatus in question, and thereafter automatically regulating or governing the action of said pump or blower to meet the service requirements of a pneumatic despatch tube system; bringing the pump or blower to a state of rest when all service requirements have been met.

Another object of my invention is to increase the efficiency of systems of this character by economizing power; new instrumentalities being employed to this end.

I preferably aim to control the action of the exhauster or blower through its prime mover or motor, but do not wish to be limited to such means. When such control is exercised over the prime mover, it is desirable that the latter be a single power unit of sufficient capacity to meet the maximum service requirements of a system of pneumatic tubes of one or more air circuits; and that the control exercised be such as to maintain, when in operation, a substantially constant working force; the volume of the air displaced being automatically varied in accordance with the demands of the service. In the preferred form of apparatus the means for controlling the power unit are adapted to bring it to rest when all useful service has been performed; mechanism being provided for utilizing a relatively slight variation in pressure in the fluid transmission medium, from a given predetermined pressure required or provided for the operation of a given pneumatic tube or air circuit. In practice said variation in pressure commonly arises from a decrease in the volume of air being ex-

hausted, when the air displacing device is being driven at a normal maximum speed; but may be due to other causes.

Another object of my invention is to provide a device in connection with said mechanism whereby the system when it has been started working may, after the attainment of proper operative conditions, then be held in operation for a predetermined and limited interval of time before automatic stoppage, means being provided for coaction with said device for preventing the running of this interval of time until said conditions first have been established.

The preferred power unit is an electric motor and I have aimed to incorporate in the system in connection with such motor an automatically actuated field controlling rheostat, the operative part of which will normally be in such a position as to permit the motor being automatically started from a state of rest without weakening the field circuit thereof by the introduction of external resistance.

These and other objects of my invention will be hereinafter referred to and the novel elements and combinations of elements whereby they may be attained will be more especially pointed out in the claims appended hereto.

I am aware, however, that various changes and modifications may be made in the system hereinafter more particularly described without departing from the spirit of the invention, and I hence desire to be limited only by the scope of said claims.

The preferred embodiment of my invention comprises a single power unit which is normally at rest; this power unit preferably being a shunt wound electric motor which is operatively connected to an exhauster. This latter is adapted through the instrumentalities of suitable pipe connections leading to a suction drum, to create a pressure below that of the atmosphere in a system of pneumatic despatch tube circuits, each of which is controlled at the suction drum by a normally closed valve which is preferably electrically controlled. The completion of a low voltage electric circuit at any despatch inlet or station of a pneumatic despatch tube circuit

serves to open the said electrically controlled valve at the suction drum of that line, and also to actuate a relay which completes an electric circuit whereby to cause the operation 5 of an automatic motor starter, bringing the motor up to its minimum speed and substantially coincident with the attainment of this minimum motor speed, the completion of an electric circuit which energizes an electro-magnetic device, mounted on the field 10 controlling rheostat, which withdraws a latch or pawl and thereby releases the arm of said rheostat. The rheostat arm is then free to move, preferably under the influence 15 of gravity, in such a direction as to cut in resistance in the motor field and increase its speed as well as that of the exhaust to which it is operatively connected; providing that a pressure adequately below that of the 20 atmosphere has not already been attained in the given tube circuit; said pressure being such as will, under the conditions imposed, result in the displacement per unit of time of a sufficient volume of air to make the 25 tube circuit efficiently operative.

In the drawings which form a part hereof, and in which like reference characters designate like parts throughout the several views, I have illustrated the preferred embodiment aforesaid; but reiterate that I do not desire to be limited to the particular form or disposition of parts shown.

Figure 1 is a somewhat diagrammatic view of a preferred form of the apparatus in question; this figure particularly showing a controlling panel used therein, its connections to a shunt motor, and one of the pneumatic despatch tube control circuits.

Fig. 2 is a front elevation of an electrically actuated air valve which is dominated by one of said control circuits.

Fig. 3 is a vertical median section of said valve.

Fig. 4 is a top view or plan of the same. 45 Fig. 5 is a detail section of said valve.

Capital letters have been applied to principal parts of the apparatus, small letters to details of these parts, and numerals to the various subsidiary elements of the 50 electrical equipment, the numerals being arranged in groups of ten or less with each group applying, as far as practicable, to related connections or parts.

55 Motor and connections thereto.

Referring first to Fig. 1, a panel A has mounted thereon a main line double pole switch B, main solenoid switch C, and low voltage relay D. Electrically connected to 60 this panel is a motor E, preferably of the variable speed, shunt-wound type, the field circuit of which motor includes a rheostat F. The latter is also mounted on the panel together with an automatic motor starter G.

Other principal parts of the apparatus 65 will be hereinafter referred to, but the relationship of the enumerated elements should first be considered.

The switch B is adapted to complete a circuit through the main line feed wires 1 70 and 2 and the fuses 3 and 4; fuse 3 being connected via a wire 5 with the contact post 10 of the main solenoid switch C. When the switch contact arm C' of said switch, which has a bias for its open position, is drawn 75 down, in the manner hereinafter described, it makes contact not only with this post but with two other posts, 11 and 12.

The effecting of contact between the arm C' and posts 11 and 12 completes two partial 80 circuits; the current flowing through contact 12 maintaining said arm in its circuit closing position; while the current flowing through 11 energizes the coil of the motor 85 starter G.

The actuation of the motor starter G first establishes the field circuit of the motor and current flows from the now energized switch arm C' through wire 13 and lead 20, to the field coils 21; thence via lead 22 and wire 23 90 to the plate 30 of rheostat F, and from there over wire 31 to the contact strip 40 of the motor starter G. The starter arm 41 will, under the described conditions, have moved upwardly into contact with strip 40 and the 95 field current will traverse this arm to pivot post 42, flowing thence over wire 43 to the fuse 4, switch B and line wire 1.

Following the partial circuits above referred to in detail, current flows from post 12, 100 through wire 14 to the solenoid switch C, thence via wires 15 and 16, resistances 17 and 18, and wire 19 to the pivot post 42, from whence it flows toward lead 1, over wire 43, fuse 4 and switch B.

Current through post 11 traverses wire 44, the solenoid 45 of the motor starter, wire 46, lamp switch 47 and wire 48 to the pivot post 42, and thence on to lead 1 as above described.

The energization of coil 45 causes the arm 41 of the motor starter to swing upwardly in the manner described so that it successively engages first the contact plate 40 above referred to and thereafter the control plates 49.

No considerable armature current can flow until the movable contact 50 carried by arm 41 engages the first of the segments 49 which is electrically connected to the 110 resistance 49'.

When this contact is effected however, current flows from lead 20 through armature 24, lead 25, wire 26, contact 27, wire 28, resistance 49' and contact 50, to and through 115 arm 41, and from thence out via pivot post 42, wire 43, etc.

As the arm 41 continues to move up-

wardly, resistance is cut out of the armature circuit and the motor speeds up.

It is desirable that a slight excess of speed be attained in order to insure the proper 5 actuation of the rheostat controlling device H, hereinafter referred to, and hence in certain cases means may be provided for introducing a resistance 30' in the field circuit. To this end, a series of contacts may be provided 10 in arcuate alignment with the contact strip 40, so that as the extremity of the arm 41 leaves the latter it successively receives the field current from wires 32, 33, 34, 35 and 36 instead of from wire 31 as herein- 15 before described.

At or about the time that the arm 41 encounters the last of this series of contacts, a yielding or spring contact 51 carried thereby engages a fixed contact 52, which energizes a 20 magnet 37 mounted on the base of rheostat F; magnet 37 receiving current via wire 38 from the wire 44 above referred to, and the circuit being completed through wire 39, contact 52, spring contact 51, arm 41, pivot 25 post 42, wire 43, etc.

Upon the arm 41 is a pin shaped, lamp switch operating finger 410 which when the arm reaches substantially its uppermost position, lifts the lamp switch 47, the upper 30 end of which may be pivoted, and current no longer flows through said switch.

The resistance 47" in shunt with switch 47 becomes effective at such time and reduces the flow of current through coil 45 to 35 a point where the magnetic field of the latter is just sufficiently strong to retain the arm 41 in its upper position. This obviously cuts down the heating of coil 45 and prolongs its life while economizing current.

40 Field rheostat control.

It will thus be seen that the magnet 37 will be energized by a strong current which will attract the armature 60 carried by a 45 pawl 61 and thereby effect the release of the field rheostat arm 62; permitting its movement counter clock-wise by the apparatus H and cutting in further resistance in the field circuit, causing the motor E to speed up and 50 drive the blower or pump I until a sufficient volume of air is being displaced from the drum J (to which the pump is connected by a conduit or pipe K) at the determined pressure for which a weight a of the 55 apparatus H has been adjusted.

Movement is imparted to the rheostat arm 62 through the instrumentality of an insulating link L, which is pivotally connected to the head of a piston rod b. This rod is carried 60 by a piston c which is adapted to reciprocate in a closed cylinder d. The upper extremity of the latter is connected by a pipe M to the drum J above referred to, and the lower end of said cylinder is provided with

a service cock H' which opens to the atmosphere and permits of regulation of the speed of movement of said piston. The pipe M is also provided with a cock M' to the same end.

Rod b extends through both heads of the 70 cylinder and carries the weight a at its lower extremity, said weight being varied to suit the particular conditions under which the system is to be operated.

75

Fluid pressure limit.

Upon the side of the field rheostat arm 62 and insulated therefrom is a contact brush 63 which is adapted to complete a normally open partial circuit by contacting with 80 posts 64 and 65. This partial circuit draws current from the wire 14; the switch G being closed in manner aforesaid. This current passes via wire 66 to contact post 65, thence through brush 63, post 64 and wire 85 67 to wire 16. In other words this so completed circuit is in parallel with the main solenoid switch coil and hence when the arm 62 of the rheostat rotates clockwise to the limit of its travel, it short circuits the main 90 solenoid switch, causing it, on account of its weakened solenoid, to open.

This disposition of the arm 62 is brought about by the development of a rarefaction of the air in the upper end of the cylinder 95 d, in excess of a determined amount, which of course is due, in turn, either to excessive speeding of the motor and thereby of the pump I, connected thereto by the belt I' or the like; or to the substantial closure of the 100 air inlet to the drum J while the motor is in normal operation.

Air valve.

The drum or reservoir J receives air from 105 at least one tube N in a known manner, and in this tube I provide an air valve O for the purpose of controlling the flow of air through the individual transmission lines or transit tubes.

In Figs. 2, 3, 4 and 5 I have exemplified a preferred construction of said valve which is herein shown to comprise a casing e within which is pivotally mounted a hinged valve plate f which carries a disk g of 115 leather or the like. Plate f is loosely mounted upon a shaft h the end of which carries a ratchet i adapted to co-act with a pawl j whereby a spring k mounted on said shaft may be placed under any desired initial or normal stress. The end of the spring k other than that attached to the shaft h bears against the hinge plate and normally holds the valve against its seat l. Plate f carries a lug m which extends through disk g; said lug being connected to a link n the other extremity of which is connected to a lug o of a diaphragm supported structure p. This 120 125

- latter may be of any suitable construction and is carried by a diaphragm q the periphery of which is clamped between the casing members e and r . The diaphragm is 5 normally forced back by spring k into a cavity s in the member r , and a conduit or passageway t leads from this cavity to a port u which opens to the atmosphere when the valve v which is normally seated upon 10 the mouth of this port is lifted. The spaces upon the respective sides of diaphragm q are in communication through a small port or bleed hole w ; the flow of air through said hole being controlled by a valve x .
- 15 The valve v is disposed upon the lower extremity of the core p' of a solenoid P ; the upper end of said core being provided with a barb or hook y which is adapted for engagement with a spring latch or catch y' . The 20 latter is given a determined bias for its latching position but may be displaced therefrom by a diaphragm z which covers a recess z' in the outer side of the casing e ; said recess being in communication with the main 25 air passage in said casing through a preferably, although of course not necessarily, small hole e' . The resistance offered by spring catch y' to displacement by its diaphragm z , may be varied by the set screw x' and determines the pressure which must be exerted against the diaphragm z in order to cause it to move to the left, as viewed in Fig. 3, to effect the release of the hook y . Obviously, once the hook y has been latched up, 30 only the establishment of a determined pressure, or rarefaction of air below atmospheric pressure in the conduit N and, by reason of the hole e' , correspondingly upon the left-hand side of the diaphragm z , will 35 effect the release of said hook.
- 40

Relay and air-valve solenoid circuit.

The relay D , above referred to, controls the main solenoid switch C since when its 45 coil 70 is energized and the core 71 thereof is thereby lifted, the contact piece 72 carried by its core makes contact with posts 73—74 and allows current to flow from the post 73 through contact 72, post 74, wires 66 and 14, 50 the winding or coil of switch C , wires 15 and 16, resistance 17 and 18, wire 19, pivot post 42 and thence out as above described.

The actuation of relay D is a preferably effected through the instrumentality of a low 55 voltage circuit such as I shall now describe.

A battery Q may be used as the source of low voltage current, a wire 80 leading therefrom being adapted to be placed in electrical communication with either one of the 60 respective air valve solenoids P . Solenoids P and 70 are in series; being connected by a wire 81; and the current returns to the battery via wire 82.

Circuit makers R and S dominate the 65 respective solenoids P , those designated R be-

ing disposed at sub-stations of the tube line while those marked S may be located at the central station. These circuit makers may, if desired, be operated entirely independently of the operation of inserting a carrier 70 into the despatch inlet, but I do not wish to be limited to this construction except where, in certain of the claims, such independence is specified.

Operation.

75

The closure of the low voltage circuit at any one of these stations R and S hence effects two results; the relay D is energized and thereby the motor is automatically 80 started and regulated in the manner above described; and the corresponding solenoid P is rendered operative and its core p' is raised and latched up by the spring catch y' .

As previously described, the motor field is 85 first energized and then the armature is permitted to receive a gradually increased current; resistance being automatically successively cut out of the armature circuit and into the field; the resistance in the armature circuit after the starting arm 41 reaches the 90 position thereof indicated by dotted lines in Fig. 1, being merely a protective one; the lamp switch 47 being open, and the armature current passing from contact 27 directly to 95 contact 27' via a bridge 41' carried by the starter arm 41, and from thence over wire 48 to pivot post 42 and out.

A momentary closure of the low voltage circuit is sufficient to accomplish the results 100 just enumerated since the closure of switch C establishes its own maintaining circuit, above described, after which only the development of a rarefaction of air in the drum J , in excess of a determined amount, 105 will normally effect the opening of said switch.

If such rarefaction occurs, due for example to excessive speed or, as is more commonly the case, to the closure of the air valve 110 N , which had previously been opened by the actuation of solenoid core p' , then the piston e will be raised to its uppermost position, which short circuits the solenoid switch in the manner aforesaid and permits its arm 115 C' to rise.

While the rheostat arm 62 is at all times free to be forced back into its solenoid switch opening position, it cannot move past the pawl 61 until the starter arm 41 attains 120 its uppermost position. After the arm 41 has been so disposed, however, the raising of pawl 61 by its magnet 37 permits the rheostat arm to respond to the fluctuations in pressure in the drum and to thereby cut resistance into or out of the field as required; the piston descending as the pressure falls and thereby introducing resistance in the field and speeding up the motor.

Normally the air valve O is closed since 130

the bleed hole *w* permits of an equalization of pressure upon the opposed sides of the diaphragm *q*; but the elevation of the core of solenoid *P* by the energization of the latter, lifts the valve *v* from its seat and admits air to chamber *s* which drives the structures *p* into the casing *e* and lifts the valve disk *g*; the valve opening covered by the latter being of less area than said dia-

10 phragm.

Air now passes through the transmission tube, it being assumed of course that the sending end of the latter is open or has been opened, and enters the drum *J*, par-

15 tially breaking the vacuum in the latter.

As the rarefaction of air in the drum becomes less, the weight *a* descends and resistance is cut into the motor field which speeds up the blower or pump and tends to restore 20 the vacuum and thus a regulating or governing action will normally be exerted as long as air valve *O* remains open.

The rarefaction in tube or conduit *N*, however, due to the opening of the air valve, 25 had previously resulted in the auxiliary diaphragm *z* being drawn into the cavity *z'* which released the barb *y* of core *p'* from its catch *y'*, allowing said core to fall and closing the port *u*. Thereafter the air in 30 cavity *s* slowly seeps out through the bleed hole *w*, allowing the spring *k* to correspondingly close the air valve.

The closure of this valve results in an immediate rarefaction of the air in the drum 35 and causes the piston *c* to ascend and to thereby successively cut resistance out of the field, decreasing the speed of the motor and the blower connected thereto, and finally effecting the closure of the short circuit 40 around the main solenoid switch. The opening of the latter stops the motor, the starter arm 41 descends, pawl 61 falls and locks the rheostat arm against further movement away from the contacts 64-65, 45 the weight of the piston effecting, however, a proper separation of these contacts from the brush 63 which co-acts therewith, and the apparatus is then set preparatory to a re-actuation of the same.

50 The catch *y'* cannot be tripped against the action of the spring inherent thereto until a predetermined pressure, sufficiently below that of the atmosphere, has been established in the transmission tube of which tube *N* 55 may form a part, and it is obvious also that the closure of the cut-off valve *O* takes place more or less rapidly according to the flow or pressure of air in the transmission tube and the amount of opening afforded by the 60 valve *x*.

The set screw *x'* affords a very simple means for determining the operating pressure at which the spring latch *y'* will yield sufficiently to permit the time element mech-

65 arius are transmitted by means of pneumatic circuits *T*, such as have been indicated in Fig. 1, is so well known to those skilled in the art as to require no special description herein. 70

In conclusion, I particularly desire to point out that while the time element mechanism employed herein is adapted to effect the closure of the air valve *O* in a determined period of time after the development 75

of a determined pressure or rarefaction of the air in the system; this period is nevertheless subject to changes in pressure in said system. In other words, for a given decrease in pressure in the tube *N*, (assuming that this decrease be sufficient to release the solenoid core *p'* after the latter has been latched up in the manner above described) the duration of the period of operation of the time element mechanism will 85 be fixed or determined at, let us say, one minute. If now, a more nearly complete vacuum be attained, for any cause, the period will necessarily be of shorter duration, but though different from the first, will 90 nevertheless be a determined period; being determined by the position of the valve *x* and the pressure or pressures in a given tube *N*.

As a matter of fact, owing to the provision of the means for regulating the speed of the pressure fluid displacing device and thereby the pressure in the system, but relatively small variations in pressure can normally occur other than possible momentary 100 changes due to the opening and closing of inlets, and the like.

The variable action of the time element mechanism, however, is of value in that it especially well adapts the system to the conditions encountered in practice in a system such as has been herein described. 105

My co-pending application for Letters Patent, Serial No. 16,472, entitled Pneumatic despatch tube apparatus, which was 110 filed March 23, 1915, is a division of the present case; the subject matter of said divisional application having first been presented herein and thereafter duly divided out of this, the parent application. 115

Claims:

1. In a pneumatic despatch tube apparatus, the combination of an electric motor having a field circuit, a pump, an electro-magnetically operated device for starting 120 said motor, co-acting means for insuring the motor being started with said field circuit relatively strong, fluid actuated means for varying the conditions in said field circuit whereby to vary the speed of said motor, and pressure fluid controlled means for stopping said motor when said pump produces a predetermined pneumatic pressure which is in excess of that required for transmission purposes. 130

2. In a pneumatic despatch tube apparatus, the combination of an electric motor having a field energizing circuit, the speed of said motor being variable in accordance with the conditions in said circuit, a pump driven by said motor, motor controlling means a portion of which is adapted to coact with said circuit, said means comprising an electro-magnetically operated device for starting said motor, fluid actuated means for varying the conditions in said circuit and thereby the speed of said motor, and pressure fluid controlled means for stopping said motor when said pump produces a predetermined pneumatic pressure which is in excess of that required for transmission purposes.
3. A pneumatic despatch tube system comprising a conduit, a pump operatively connected thereto, means, including a low voltage electric control circuit, for rendering operative said pump, and automatic means for varying the speed of said pump when in operation according to the service demands of the system and for rendering said pump inoperative when the pressure fluid in a determined portion of said system exerts a predetermined pressure.
4. A pneumatic despatch tube system comprising a conduit, a pump operatively connected thereto, an electric motor for driving said pump, said motor having armature and field circuits, fluid pressure controlled means co-acting with one of said circuits for varying the speed of said motor substantially in accordance with the service requirements in said system, and means for maintaining said last mentioned means substantially inoperative until predetermined conditions have been established in a circuit of said motor.
5. A pneumatic despatch tube system comprising a conduit, a pump operatively connected thereto, an electric motor for driving said pump, said motor having armature and field circuits, fluid pressure controlled means co-acting with one of said circuits for varying the speed of said motor substantially in accordance with the service requirements in said system, and means for maintaining said last mentioned means substantially inoperative until predetermined conditions have been established in the armature circuit of said motor.
6. A pneumatic despatch tube system comprising a conduit, a pump operatively connected thereto, an electric motor for driving said pump, a starting device for said motor, means for rendering said starting device operative, said starting device having a part adapted to move in a determined path, a rheostat having a movable member for controlling said motor when in normal operation, means controlled by said part of said starting device for initially impeding the movement of said member, and pressure fluid controlled means for actuating said member.
7. A pneumatic despatch tube system comprising a conduit, a pump operatively connected thereto, an electric motor for driving said pump, a starting device for said motor, said starting device having a movable part, means including a low voltage circuit having a relay therein, for rendering said starting device operative, fluid pressure controlled means for varying the speed of said motor when in normal operation, and connections between said starting device and said fluid pressure controlled means whereby the latter is maintained substantially inoperative until said movable part of said starting device is disposed in a determined position.
8. A pneumatic despatch tube system comprising a conduit, a pump operatively connected thereto, an electric motor for driving said pump, said motor having armature and field circuits, means for controlling one at least of said circuits, said means including an electro-magnetically controlled switch, means for closing said switch and starting said motor and pump from a distant point along said conduit and means for insuring the opening of said switch when a determined fluid pressure is developed in a determined portion of said system.
9. A pneumatic despatch tube system comprising a conduit, a pump operatively connected thereto, an electric motor for driving said pump, said motor having armature and field circuits, means for controlling said circuits, said means including a main switch, means for closing said switch from a distant point along said conduit and means for insuring the opening of said switch when a predetermined fluid pressure is developed in a determined portion of said system.
10. In combination in a pneumatic despatch tube apparatus, a conduit, a pump operatively connected thereto, an electric motor for driving said device, a starting pump for said motor, a rheostat for controlling said motor when in operation, fluid pressure controlled means for actuating a part of said rheostat, a valve in said conduit, fluid pressure controlled means for actuating said valve, and means co-acting with said valve, said rheostat part and the means for actuating the latter, for insuring the stoppage of the motor when a predetermined fluid pressure is attained in a determined portion of the system.
11. A pneumatic despatch tube apparatus comprising an exhauster, an electric motor for driving the same, a normally open, electro-magnetic main switch for said motor, a low tension circuit including a relay for initially controlling the flow of current through said main switch, a motor starter 120
- 125
- 130

- in circuit with said switch, a maintaining circuit for said switch when closed, and means for insuring the opening of said switch substantially when a predetermined rarefaction of the air is effected by said exhauster in a portion of said system.
12. A pneumatic despatch tube apparatus comprising a conduit, a pump, an electric motor for driving the latter, a normally open electro-magnetic main switch for said motor, means for initially controlling the flow of current through said main switch, a motor starter in circuit with said switch, a maintaining circuit for said switch when closed, and means for insuring the opening of said switch substantially when a predetermined pressure of air is produced by said pump in a portion of said conduit.
13. A pneumatic despatch tube apparatus comprising a conduit, an exhauster connected thereto, an electric motor for driving the exhauster, and means for starting the motor, in combination with means for regulating the speed of the motor in response to pressure in the conduit when the motor is permitted to run, and automatic means acting in consequence of occurrence of flow of air through said conduit for stopping the motor, said automatic means being operative after flow at a predetermined pressure during a predetermined interval of time, and being inoperative prior to establishment of flow at such pressure.
14. A pneumatic despatch tube apparatus comprising a conduit, an exhauster connected thereto, an electric motor for driving said exhauster, and means for starting the motor, in combination with automatic means acting in consequence of occurrence of flow of air through said conduit for stopping the motor, said automatic means being operative after flow at predetermined pressure for a predetermined interval of time, and being inoperative prior to establishment of flow at such pressure.
15. A pneumatic despatch tube system comprising a conduit, a pump for said conduit, means for regulating the action of said pump, said means including a movable part the position of which substantially determines the speed of said pump, means for holding said part against movement in one direction until said pump is running substantially normally, means for releasing said part when such condition is attained, and means for moving said part in accordance with variations in pressure in a part of said system.
16. A pneumatic despatch tube system comprising a conduit, a pump for said conduit, means for regulating the action of said pump, said means including a movable part, the position of which substantially determines the speed of said pump, means for holding said part against movement in one direction until said pump is running substantially normally, means for releasing said part when such condition is attained, and means for moving said part in accordance with variations in pressure in a part of said system.
17. A pneumatic despatch tube system comprising a conduit, a pump for said conduit, means for regulating the action of said pump, said means including a movable part, the position of which substantially determines the speed of said pump, means for holding said part against movement in one direction until said pump is running substantially normally, means for releasing said part when such condition is attained, and means for moving said part in accordance with variations in pressure in a part of said system, and means co-acting with said regulating means for stopping said pump upon the development of a predetermined pressure in a portion of said system.
18. A pneumatic despatch tube system comprising a conduit, a pump operatively connected to said conduit, means for starting said pump, means for maintaining it in operation, when started, at least until a given fluid pressure is attained in a determined portion of said system, means for adjusting a portion of said maintaining means to determine the given fluid pressure aforesaid at the amount desired, and means for normally stopping said pump within a determined time interval after the attainment of the given pressure in manner aforesaid.
19. In a pneumatic despatch tube system for carriers, having sending and delivery stations, the combination of a conduit, a pump operatively connected thereto, means for starting said pump, said means including a controlling part therefor disposed substantially at said sending station, said controlling part being movable independently of the despatch of carriers at said station, and means for automatically stopping said pump after the lapse of a determined interval of time subsequent to the establishment of a determined operating condition in a portion of said system.
20. A pneumatic despatch system of the type including a conduit for carriers and means causing carrier-driving changes of pressure in the conduit for the purpose of driving a carrier, having therein in combination with the conduit and the air-displacing means therefor, a motor for driving said means, automatic means for varying the speed of the motor in response to the

- pressure in a part of the system, means for stopping the motor when the pressure reaches a predetermined limit, a valve between the conduit and air-displacing means, electrically controlled means operated from a distant part of the conduit for opening the valve, and starting means for the motor actuated upon operation of said electrically controlled means.
21. In a pneumatic despatch tube apparatus, a conduit, a pump connected thereto, a valve for throttling the flow of fluid through said conduit, means for operating said valve, means to co-act with parts of said valve operating means to determine an extended period of time during which said valve must remain open, an electric circuit for transmitting an actuating impulse to said valve operating means, means to prevent the running of said time period determining means and acting to restrain a part of said operating means against movement after being actuated by said impulse, and fluid pressure controlled means for releasing said part upon the development of a determined pressure in said conduit, to permit the timing means to become operative.
22. In a pneumatic despatch tube apparatus, a conduit, the air in which is normally at atmospheric pressure, a pump connected thereto, a valve for throttling the flow of fluid through said conduit, means for operating said valve, means to co-act with parts of said valve operating means to determine an extended period of time during which said valve must remain open, said pump being in communication through said conduit with the outer air only so long as said valve is open, means for transmitting an actuating impulse to said valve operating means, latching means to prevent the running of said time period determining means and acting positively to restrain a part of said operating means against movement after being actuated by said impulse until said pump has effected a departure from normal atmospheric pressure in a portion of said conduit in excess of a determined amount, and pressure responsive means for releasing said part from said latching means when the said departure from said pressure is attained.
23. In a pneumatic despatch tube apparatus, a conduit, the air in which is usually at atmospheric pressure, a pump connected thereto, a valve for throttling the flow of air through said conduit, said valve having a bias for its closed position, means for displacing said valve from said position, time element means for controlling the movement of said valve back to said determined position when displaced therefrom, and means for rendering said time element means inoperative after said valve has been opened until a determined change in pressure

of the air in a portion of said conduit has been attained.

24. In a pneumatic despatch tube system comprising a conduit a part of which constitutes a transit tube, a pump operatively connected thereto, means for rendering said pump operative, time element means, means to be automatically operated after said pump has become operative, to coact with said time element means to establish a determined period of time and to stop said pump at the end of said period, and automatic pressure responsive means to cause said last mentioned means to establish said period only after the establishment of determined pressure conditions in a part of said conduit.

25. In combination in a pneumatic despatch tube system, having sending and delivery stations, a conduit, a pump operatively connected thereto, a mechanism for driving said pump, means for starting said mechanism and pump substantially simultaneously, said means including a controlling element therefor disposed at a sending station in said system, and means controlled only in part by said controlling element, for automatically stopping said mechanism and pump after the lapse of a normally determined but extensible period of time running only from and after the establishment of a determined operating pressure in a portion of said system, each actuation of said controlling element during the running of said period extending said period by a determined amount, said last mentioned means including a normally closed valve in said conduit, means for opening said valve and means controlled by the pressure in said conduit and rendered inoperative when said operating pressure is established for maintaining said valve open at least until said determined pressure is established.

26. In combination in a pneumatic despatch tube system, having sending and delivery stations, a conduit, a pump operatively connected thereto, a mechanism for driving said pump, means for starting said mechanism and pump, said means including a controlling part therefor disposed substantially at a sending station in said system, and means for automatically stopping said mechanism and pump after the lapse of a normally determined but extensible period of time running only from and after the establishment of a determined operating pressure in a portion of said system, said last mentioned means including a normally closed valve and means controlled by the pressure in said conduit and rendered inoperative when said pressure is established for maintaining said valve open at least until said determining pressure is established, said means for opening said valve being also controlled by the controlling part aforesaid.

and operatively responding to each actuation of said part during said period of time to extend the latter.

- 5 27. In combination in a pneumatic despatch tube system, a branched conduit, a pump operatively connected thereto, a normally idle mechanism for driving said pump, a plurality of normally closed valves 35
 10 any desired number of which may be open at the same time, one of said valves being in each of the branches of said conduit to control the flow therethrough of pressure fluid displaced by said pump, means for 40
 15 substantially simultaneously starting said normally idle mechanism and opening any desired one of said valves, means, operable while said mechanism is in operation, for opening another of said valves, and means 45
 20 to close each of the opened valves after the lapse of a determined period of time, each valve being separately timed, said valve opening means each having provisions for extending by a determined amount said 50
 25 period for the valve corresponding to such means and during the running of said period.

28. In combination in a pneumatic despatch tube system, a branched conduit, a pump operatively connected thereto, a mechanism for driving said pump, a valve in at 55
 30 least one of the branches of said conduit to

control the flow therethrough of pressure fluid displaced by said pump, said valve being open or closed as desired when said pump is operative, and means, portions of which are common to both said mechanism and said valve, for starting said mechanism if idle and for opening said valve whether said mechanism be idle or in operation. 40

29. In combination in a pneumatic despatch tube system, a branched conduit, a pump operatively connected thereto, a normally idle mechanism for driving said pump, a valve in each branch of said conduit adapted to control the flow through the corresponding branch of pressure fluid displaced by said pump, means for substantially simultaneously opening any one of said valves and independently of the latter 50 to start said normally idle mechanism to drive said pump, means for maintaining said pump in operation so long as any one of said valves is open, and means co-acting with the last valve to close to automatically 55 stop said mechanism.

In testimony whereof I have affixed my signature, in the presence of two witnesses.

ALBERT W. PEARSALL.
